UNITED STATES PATENT OFFICE.

ARTHUR H. SWANK, OF FREMONT, OHIO.

KNIFE HANDLE.

Application filed November 19, 1926. Serial No. 149,412.

The present invention is directed to improvements in knife handles, and more particularly to a handle for a knife of the type designed for paring fruit and vegetables.

5 The primary object of the invention is to provide an article of this character having a novel form of handle which not only performs its function, but serves as means for permanently retaining panels bearing advertising data.

10 Another object of the invention is to provide an article of this kind which includes an integrally connected blade and shank, the shank being of such construction that the 15 handle can be conveniently secured thereon in order to provide a simple and comfortable hand grip.

In the accompanying drawings:

Figure 1 is a side elevation of the device.
20 Figure 2 is a sectional view on line 2—2 of Figure 1.

Figure 3 is a sectional view on line 3—3 of Figure 1.

25 Referring to the drawing, 1 designates the blade and 2 the shank thereof, said shank and blade being formed from a blank of suitable steel. The blade 1 is preferably concaved, as at 3, in order to define an effective cutting edge, and this blade may be polished or finished in any approved manner.

30 The handle 4 is formed from a single length of non-rust metal so bent as to provide a U-shaped frame 5 having a continuous channel 6 formed therein to provide relatively narrow side walls 7 in order to provide considerable space between the side bars of the frame for the display of advertising matter.

35 The shank 2 has its rear end rounded in order to fit into the bight portion of the frame and it will be observed that one of the side bars is somewhat longer than the other in order that the blade 1 will be strengthened at the point subjected to the most strain when paring.

40 The numeral 8 designates the panels upon which the advertising matter is printed, and these panels may be formed from celluloid, veneer, or metal, and to place the panels, 45 handle and shank in assembled relationship, a panel is placed upon each side of the shank

2 and the parts thus assembled inserted in the frame 5, following the groove thereof until the rear end of the shank snugly engages the bight portion of the frame. To 55 firmly retain the frame in place, the side walls 7 thereof are pressed inwardly in any approved manner, thus firmly securing the panels and shank in their proper relationship with respect to the handle frame. If desired, the panels 8 may be first placed in the channel or groove of the frame and the shank inserted therebetween, after which the sides of the frame may be pressed.

55 The panels 8, as well as the shank, may be 60 perforated, as at 9, in order that the device can be suspended in a convenient location when not in use.

65 From the foregoing, it will be observed that a knife has been provided having an 70 extremely simple handle, which not only affords a comfortable grip, but also serves to permanently retain advertising matter, thus providing an exceedingly attractive and simply constructed advertising medium.

75 Paring knives are usually provided with thick and cumbersome wooden or metal handles, whereas I have provided a handle which is comparatively thin in order that the same can be comfortably and firmly gripped, and 80 will prevent the handle from slipping when in use. The blade is flexible and is formed from a blank of thin rust and satin proof steel, and owing to the flexibility thereof the 85 paring operation is greatly facilitated since the blade will conform to the contour of the article being pared and is extremely sensitive to pressure.

Having thus described the invention, what I claim is:

90 The combination with a knife blade having an integral shank, of a U-shaped frame formed from a single length of material and having a continuous channel therein for receiving the edges of the shank, panels for 95 advertisement engaged with the sides of the shank, and received in said channel, said frame being pressed to firmly hold the panels engaged against the shank and shank confined within the frame.

100 In testimony whereof I affix my signature.

ARTHUR H. SWANK.
